UNITED STATES PATENT OFFICE.

GEORGE E. STUDDY, OF EARLS COURT, ENGLAND.

DESIGN FOR A STATUETTE.

Application filed October 4, 1924. Serial No. 10,970. Term of patent 3½ years.

To all whom it may concern:

Be it known that I, GEORGE E. STUDDY, a subject of the King of England, residing at Earls Court, in the county of London, England, have invented a new, original, and ornamental Design for Statuettes, of which the following is a specification, reference being had to the accompanying drawing, forming part thereof.

The figure is a perspective view of a statuette, showing my new design.

I claim:

The ornamental design for a statuette, as shown.

GEORGE E. STUDDY.
